(57) **CLAIM**

The ornamental design for a set of side panels for a transport vehicle, as shown and described.

DESCRIPTION

FIG. 1 is a left side view of the set of side panels for a transport vehicle, in accordance with the present invention; FIG. 2 is a right side view of the set of side panels for a transport vehicle;

FIG. 3 is a front view of the set of side panels for a transport vehicle;

FIG. 4 is a rear view of the set of side panels for a transport vehicle;

FIG. 5 is a top view of the set of side panels for a transport vehicle;

FIG. 6 is a perspective view of FIG. 1;

FIG. 7 is a perspective view of FIG. 2;

FIG. 8 is an enlarged side view of FIG. 1 shown with the environmental structure removed;

FIG. 9 is an enlarged side view of FIG. 2 shown with the environmental structure removed;

FIG. 10 is a perspective view of FIG. 8; and

FIG. 11 is a perspective view of FIG. 9.

The broken line showing of the transport vehicle is for illustrative purposes only and forms no part of the claimed design.

CERTIFICATE OF CORRECTION

PATENT NO. : Des. 521,413 S
APPLICATION NO. : 29/188376
DATED : May 23, 2006
INVENTOR(S) : Katoh

Page 1 of 12

It is certified that error appears in the above-identified patent and that said Letters Patent is hereby corrected as shown below:

The Title Page, Showing an Illustrative Figure, Should be **Deleted** and **Substitute** therefor the Attached Title Page.

Delete Drawing Sheets 1 - 6 and **Substitute** therefor the Drawing Sheets Consisting of Figs 1-11 as Shown on the Attached Pages.

Signed and Sealed this

Second Day of December, 2008

JON W. DUDAS
Director of the United States Patent and Trademark Office

CLAIM

(22) Filed: **Aug. 18, 2003**

The ornamental design for a set of side panels for a transport vehicle, as shown and described.

(30) **Foreign Application Priority Data**

Jun. 6, 2003 (JP) 2003-016052

DESCRIPTION

(51) **LOC (8) CL** **12-14**

FIG. 1 is a left side view of the set of side panels for a transport vehicle, in accordance with the present invention; FIG. 2 is a right side view of the set of side panels for a transport vehicle;

(52) **U.S. CL** **D12/1; D12/16**

FIG. 3 is a front view of the set of side panels for a transport vehicle;

(58) **Field of Classification Search** **D12/1,**

FIG. 4 is a rear view of the set of side panels for a transport vehicle;

D12/400, 196, 14-16, 107, 82, 86-93; D15/28,
D15/30; D21/803; 180/233, 908; 280/DIG. 5;
296/183-186, 28, 37.7

FIG. 5 is a top view of the set of side panels for a transport vehicle;

See application file for complete search history.

FIG. 6 is a perspective view of FIG. 1;

(56) **References Cited**

U.S. PATENT DOCUMENTS

FIG. 7 is a perspective view of FIG. 2;
